UNITED STATES PATENT OFFICE.

RICHARD A. BYRNE, OF PHILADELPHIA, PENNSYLVANIA.

DESIGN FOR A BLANK FOR ENVELOPS.

SPECIFICATION forming part of Design No. 30,943, dated June 6, 1899.

Application filed April 28, 1899. Serial No. 714,919. Term of patent 14 years.

To all whom it may concern:

Be it known that I, RICHARD A. BYRNE, a citizen of the United States, residing at the city of Philadelphia, in the county of Philadelphia and State of Pennsylvania, have invented and produced a new and original Design for Blanks for Envelops, of which the following is a specification, reference being had to the accompanying drawing, forming part thereof and illustrating in top or plan view a blank for an envelop, showing my design.

The leading or material feature of my design consists of the configuration or outline of the envelop-blank.

As illustrated in the drawing, the blank consists of a rectangular central panel or field a , from the longer sides $a' a'$ of which project the two triangular flaps $b b$, the apices $b' b'$ of which are rounded and the bases of which are slightly shorter than the sides $a' a'$ of the

field a . From one of the shorter sides a^2 of field a projects the triangular flap d , the apex d^3 of which is rounded, and from the other side a^3 projects the substantially square panel or flap d' , the corners d^2 of which are rounded. ²⁵ The bases of the triangular flaps $b b$ do not extend to the side a^3 of the field a , but stop at the points $a^4 a^4$ below said side a^3 .

Having thus described my invention, what I claim as new, and desire to secure by Letters ³⁰ Patent, is—

The design for a blank for an envelop, as herein described and illustrated.

In testimony whereof I have hereunto set my signature in the presence of two subscribing witnesses.

RICHARD A. BYRNE.
